WATER CLOSET

Cesare C. Campus, Santa Monica, Calif.

Application February 10, 1936, Serial No. 63,050

8 Claims.

(Cl. 4—69)

This invention relates to a water closet, and particularly to a novel construction of the trap and other features more specifically herewith described.

5 One of the objects of my invention is to eliminate the inconvenience of warping the base of the closet bowl when it is being fired, by enlarging the front and rear end of the trap leaving only a central portion thereof, of the same dimensions and shape of an ordinary trap, (suggesting an elongated figure eight) which ordinarily is shaped evenly and parallel from one end to the other, but proved to be not wide enough to prevent warping of the base.

10 15 It is obvious that this type of construction will substantially brace the base of the bowl. The bowl is fired the first time in an up-side-down position to keep the weight off the base; although said base is lighter than the top, if not properly braced, it will warp. After the first firing, the closet bowl is glazed, and then put back for the second firing, in the upright position.

This invention, therefore, prevents unnecessary waste caused by warping when the bowl is being fired, or by producing second or third-grade goods which cannot be sold at top price, which substantially decreases the profits.

Another object of my invention is to provide 30 the top of the trap with an air pocket or pockets to eliminate the gurgle of the water, which occurs at the end of the flushing, as the air in the pocket will gradually expand into the empty space left in the trap, thus reducing the vacuum action, thereby substantially moderating the onrush of the air, which enters the mouth of the trap before the refilling of the bowl takes place.

A further object of my invention is to facilitate the crating of the bowl, to prevent breakage 40 and chipping in handling, and to facilitate the plumber in taking measurements to connect the bowl to the water line, by having the rear and the front ends flat and parallel, as shown in my preferred form illustrated in Figs. 3 and 4.

45 All the above described improvements can be adapted to any type of water closet and the enlarged front and rear end of the trap can be made of any suitable shape.

50 The foregoing objects and advantages with my subsequent features that may be developed in the description, may be best appreciated from the description read in conjunction with the drawings, in which:

55 Fig. 1 is a side elevation in section, of the bowl.

Fig. 2 is a top plan view of the bowl, partially sectioned on lines 1, 2 and 3 of Fig. 1.

Fig. 3 is another form of the invention with a perpendicular front.

Fig. 4 is a front elevation of Fig. 3.

Fig. 5 is the perimeter resulting from a section on lines 3—3 of Fig. 3.

Fig. 6 is a plan view of Fig. 4.

Fig. 7 shows another form of the perimeter of the bowl.

Fig. 8 represents a side elevation of another form of the invention.

Fig. 9 represents a front elevation of Fig. 8.

Fig. 10 represents a plan view of the perimeter of the bowl sectioned on line 4—4 of Fig. 8.

Fig. 11 is a top plan view of Fig. 9.

The construction of my invention, shown in Figs. 1 to 11 inclusive is as follows:

7 in Fig. 1 represents the water closet carrying trap 8 provided at the top with air pocket 9, 20 which will be constantly provided with air that will gradually expand before the bowl is completely flushed, thus moderating the onrush of the air into said trap 8, as soon as the water level has receded below mouth 10 of trap 8, thus 25 preventing the gurgling sound. Air pocket 9 is formed by the outline of the front end of trap 8, (more clearly shown in Fig. 2) and by the upper wall of trap 8, resulting in a hood-shaped pocket.

30 Fig. 2 represents a top plan view of Fig. 1, partially sectioned on lines 1, 2 and 3 of Fig. 1, showing the shape of pocket 9 and of base 12 of the bowl.

35 Fig. 3 is an outside elevation view of another form of the invention with two distinct characteristics, one of which is, that the front and rear end of the bowl are parallel for the entire height of the bowl, which facilitates the handling and crating, prevents breaking and chipping, and permits the bowl to lie flat on either of the two said ends.

40 Fig. 4 represents the front elevation view of Fig. 3, and shows, that having enlarged the front end of the trap, the belly of the bowl is partially hidden, thus giving the effect of being a vase rather than a water closet.

45 Fig. 5 in broken line, shows the perimeter of the section on line 3—3 of Fig. 3 which shows that the base of the bowl is formed in combination with both ends of the enlarged trap, thus substantially differing from the base of any ordinary bowl, which usually protrudes from both ends of the trap, as shown in Fig. 10.

55

Fig. 6 is a top plan view of Fig. 4, showing the flat front on which the bowl can lie flat.

Fig. 7 shows in broken lines the perimeter of the widened ends of the trap, shaped round instead of being a combination of straight lines, as shown in Fig. 5; of course this shape can be changed to suit.

Fig. 8 shows another form of the invention, of a more conventional type, except that the front and rear end of the trap are enlarged, but the flanged base protrudes all around the perimeter of the bowl on line 4—4, as more clearly shown in Fig. 10.

Fig. 9 is an elevation front view of Fig. 8.
15 Fig. 10 represents the perimeter of the closet bowl on lines 4—4 of Fig. 8.

Fig. 11 shows a top plan view of Fig. 9.

From the foregoing description, it will be seen that the purpose of my invention has been accomplished by the device as shown, economically and without complications, and by having reduced already to practice, said invention, the advantages herein described have proven to be real and of substantial merit.

25 Although I have shown the different forms of my invention, I am aware that to those skilled in the art, other forms will readily suggest themselves, it is therefore, my intention to include all such forms and modifications in the nature of 30 technicalities and refinements of my invention that come within the range and scope of the invention, as expressed in the appended claims;

What I claim as my invention, and desire to secure by Letters Patent is:

35 1. A water closet having a bowl, a trap therein, the front and rear ends of the water closet being provided with vertically extending tubular reinforcements of greater width than the intermediate portion of the trap.

40 2. A water closet having a bowl, a trap, the

front and rear ends of the water closet being provided with vertically extending tubular reinforcements of greater width than the intermediate portion of the trap and extending on opposite sides thereof.

3. A water closet having a trap, the front end of the trap being enlarged with respect to the remaining portion thereof, the rear end of the water closet opposite the trap being correspondingly enlarged.

4. A water closet having a trap, the front end of the trap being enlarged with respect to the remaining portion thereof, the rear end of the water closet opposite the trap being correspondingly enlarged and horizontally extending base 15 flanges on opposite sides of the trap connecting the front and rear enlargements.

5. A water closet having a trap, the front end of the trap being enlarged with respect to the remaining portion thereof, the rear end of the water closet opposite the trap being correspondingly enlarged and horizontally extending base 20 flanges on opposite sides of the trap connecting the front and rear enlargements, said flanges terminating short of the front and rear ends of the 25 water closet.

6. A water closet comprising a bowl, a base for said bowl, the front face of the water closet being flat and extending from the bottom of the base to the top of the bowl.

7. A water closet comprising a bowl, a base therefor, the front and rear faces of the water closet being flat and extending from the bottom of the base to the top of the bowl substantially 30 perpendicular to said base.

8. A water closet comprising a bowl, and a base therefor, the front and rear of the water closet presenting parallel faces extending from the bottom of the base to the top of the bowl.

CESARE C. CAMPUS. 40
